Patented Oct. 5, 1920.

UNITED STATES PATENT OFFICE.

CORNELIUS DANAHER, OF PHILADELPHIA, PENNSYLVANIA.

GAS-LAMP.

1,354,730.

Specification of Letters Patent.

Patented Oct. 5, 1920.

Application filed February 4, 1920. Serial No. 356,157.

To all whom it may concern:

Be it known that I, CORNELIUS DANAHER, a citizen of the United States, residing at Philadelphia, in the county of Philadelphia and State of Pennsylvania, have invented a new and useful Gas-Lamp, of which the following is a specification.

The device forming the subject matter of this application is a gas lamp, and one object 10 of the invention is to provide novel means for holding the globes in place with respect to the burner structure.

Another object of the invention is to provide a gas lamp so constructed that the passage 15 of the products of combustion will be encumbered to a minimum extent.

Another object is to improve generally and to enhance the utility of devices of that type to which the invention appertains.

20 With the above and other objects in view, which will appear as the description proceeds, the invention resides in the combination and arrangement of parts and in the details of construction hereinafter described and claimed, it being understood that, within 25 the scope of what is claimed, changes in the precise embodiment of the invention shown can be made without departing from the spirit of the invention.

30 In the accompanying drawings:—

Figure 1 shows in side elevation, a device constructed in accordance with the invention, parts being broken away;

Fig. 2 is a top plan wherein parts are 35 omitted; Fig. 3 is a section taken approximately on the line 3—3 of Fig. 2; Fig. 4 is a fragmental transverse section showing a slight modification in the invention; and Fig. 5 is a section taken approximately on 40 the line 5—5 of Fig. 4.

The device forming the subject matter of this application includes an annular body comprising a strip 1 of mica, surrounded by a strip 2 of colored material, such as 45 ribbon. The strips 1 and 2 are embraced, at intervals, by transverse members 3 of inverted U-shape, the parts above described being engaged at their upper edges by a top ring 4 of inverted U-shape, and being em- 50 braced at their lower edges by a bottom ring 5 of U-shape. The outer walls of the members 3 are provided with inclined lips, extended circumferentially of the annular body above alluded to, the lips 8 being

adapted to engage the beveled edges 6 of 55 transparent pieces 7, which may be made of glass or any other suitable material, the ends of said pieces resting against the inner walls of the members 3, as indicated best in Fig. 4. It will be seen that the members 3 60 are so constructed that the glass pieces 7 may be used in place of the strip 1 of mica and the strip 2 of colored material, if desired. The construction alluded to permits the manufacturer to make up the annular 65 body in a variety of ways, as occasion may demand.

The body above described supports an upper globe 9. A lower globe 10 coöperates with the body and is held in place by 70 set screws 11 extended through the bottom ring 5 and adjacent parts. A relatively small Bunsen tube 12 passes through the body and communicates with a gas supply pipe 14, the Bunsen tube having a suitable 75 air control 15 of any desired construction.

The numeral 16 denotes an L-shaped member having a tapered bore 17, the L-shaped member embodying an end wall 18 receiving the inner end of the Bunsen 80 tube 12. The upper end of the L-shaped member 16 has an offset annular flange 19. The numeral 20 denotes, generally, a gooseneck, including cylindrical ends 21 and 22 and a flattened crown 23. The cylindrical 85 end 21 of the gooseneck 20 is held frictionally in the flange 19 of the member 16, to afford a slip joint, the cylindrical end 22 being held frictionally in a mantle support 24 of any desired construction, to afford a 90 slip joint. A piece of gauze 100 is located in the mantle support 24 at the inner end of the part 22.

A pilot tube 25 extends through the body, adjacent to the member 16 and carries a 95 pilot burner 26, the function of which is clearly understood by those skilled in the art.

In the outer surface of the member 16, a seat 27, which may be V-shape, is formed, 100 the seat being adapted to receive a correspondingly shaped rib 28 formed on the intermediate portion 29 of a horizontally disposed bracket 30, including arms 31 having enlargements 32 connected by screws 105 33 with the body, above mentioned. A screw 34 extends through the intermediate portion 29 of the bracket 30 and holds the

same on the member 16, and since the intermediate portion 29 of the bracket is provided with the rib 28, received in the seat 29, it will be obvious that the bracket cannot 5 tilt laterally with respect to the member 16. The bracket 30, of course, serves as a support for the annular body and for the globes 9 and 10. Since the diameter of the Bunsen tube 12 is relatively small, compared with 10 the diameter of the bore 17 of the member 16, back pressure in the Bunsen tube will be reduced to a minimum. Owing to the fact that the gooseneck 20 is flattened or thinned transversely as indicated at 23, the 15 heated air and the products of combustion will find a ready exit, and their passage will be encumbered and impeded to a minimum extent.

In devices of the kind hereinbefore described, a considerable amount of difficulty has been experienced, owing to the fact that the gauze 100 will choke up, notably with dust taken in with the air at the inlet 15. As a consequence, it is often necessary to 20 remove the gooseneck 20 from the member 16 and from the mantle support 24. The practice heretofore has been to remove the member 16 from the Bunsen tube 12 but these parts generally are threaded, together 25 30 and since the Bunsen tube 12 is of small diameter, the Bunsen tube is likely to be twisted off or broken. Again, if the gooseneck 20 is threaded to the burner support 24 and to the member 16 much difficulty is experienced in separating these parts, in order 35 to get at the gauze 100. If the gooseneck 20 is threaded at its ends to the burner support 24 and to the member 16, the parts become baked together owing to the intense 40 heat. In the device forming the subject matter of this application, there are slip joints between the parts 21 and 19, and, preferably, between the parts 22 and 24. The gooseneck 20, therefore, may be lifted 45 readily off the member 16 and the mantle support 24 may be removed from the gooseneck with equal facility, it being necessary, merely, to separate the parts by a sliding movement. In devices of the sort hereinbefore described, where the parts are threaded together, it is necessary, not infrequently, to call into requisition the services of a pipefitter or lamp expert, since 50 a device of this kind cannot be taken apart and assembled by a person of average or less than average mechanical ingenuity. The slip joints which form one of the characteristic features of this invention, make it possible to take the device apart and to 55 set it up again, practically without the use of tools, and the operation may be carried on by a person having small mechanical skill. The ease with which the parts may be separated, prevents an injury to the 60 mantle, resulting from jars, a mantle being 65

as is well known an exceedingly delicate article. Since the gauze 100 can be removed without difficulty, the device will not become foul and a discoloration of the ceiling 70 will be prevented.

A gas mantle may be damaged in the factory, in a store, or before it is placed on a gas lamp, by the handling of the mantle, or otherwise. If the mantle has been dented or creased, that defect cannot be detected 75 until the mantle is burned off, the mantle being treated with a coating of collodion to keep it together until it is put on a gas burner and ready for use. The operator burns off the mantle and the defects in the 80 mantle appear, and if the mantle has been dented a piece will fall out, or if the mantle has been creased, the mantle will crack open. Thus, in either case, an opening is formed in the mantle through which opening the 85 flame is bound to shoot. In gas lamps as at present constructed, the flame shooting through the opening as above described, tends to crack the glass, on account of the glass being so close to the mantle. In the 90 lamp forming the subject matter of this application, the flame cannot reach the glass. Therefore, although the mantle may have been damaged, the mantle may still be used and there is no occasion for purchasing a 95 new mantle and throwing the old one away. The device forming the subject matter of this application obviously provides a means whereby defective mantles may be used without endangering the glass portion of 100 the lamp, a saving being effected, since mantles, hitherto subject to destruction as being defective, may be employed to advantage, and without danger to the lamp.

Having thus described the invention, what 105 is claimed is:

1. In a device of the class described, an annular body, a globe supported by the body; a Bunsen tube passing through the body; an angle member connected with the 110 Bunsen tube; a gooseneck communicating with the angle member, the gooseneck being thinned intermediate its ends; and a mantle support carried by the gooseneck.

2. In a device of the class described, an 115 annular body; a Bunsen tube passing through the body; an angle member communicating with the Bunsen tube; a gooseneck forming a continuation of the angle member; a mantle support assembled with 120 the gooseneck; and a bracket connected with the angle member and with the body.

3. In a device of the class described, an 125 annular body; an angle member within the body; means for supplying fuel to the angle member; a gooseneck assembled with the angle member; a mantle support carried by the gooseneck; and a bracket including diverging arms, the extremities of the arms being connected to the body, and the inter- 130

mediate portion of the bracket being connected to the angle member.

4. In a device of the class described, an annular body including top and bottom 5 rings of U-shape; and transverse members received within the rings, the transverse members comprising outer and inner walls, the outer walls being provided with outwardly extended lips inclined circumferen-

tially of the body and located between the 10 rings.

In testimony that I claim the foregoing as my own, I have hereto affixed my signature in the presence of two witnesses.

CORNELIUS DANAHER.
